US00D905749S

(12) **United States Design Patent** (10) **Patent No.:** **US D905,749 S**
(45) **Date of Patent:** **** Dec. 22, 2020**

(54) **DISPLAY SCREEN OR PORTION THEREOF WITH ICON**

(71) Applicant: **Apple Inc.**, Cupertino, CA (US)

(72) Inventors: **Richard D. Lyons**, San Francisco, CA (US); **Christopher Wilson**, San Francisco, CA (US)

(**) Term: **15 Years**

(21) Appl. No.: **29/728,083**

(22) Filed: **Mar. 16, 2020**

Related U.S. Application Data

(63) Continuation of application No. 29/688,447, filed on Apr. 22, 2019, now Pat. No. Des. 879,144, which is a continuation of application No. 29/610,178, filed on Jul. 10, 2017, now Pat. No. Des. 846,594.

(57) **CLAIM**

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is another embodiment thereof.

The broken lines in the figures show a display screen or portion thereof, and form no part of the claimed design.

PATENT NO. : D905,749 S
APPLICATION NO. : 29/728083
DATED : December 22, 2020
INVENTOR(S) : Lyons et al.

Page 1 of 2

It is certified that error appears in the above-identified patent and that said Letters Patent is hereby corrected as shown below:

On the Title Page

Replace the illustrative print figure, Figure 1, with the corrected Figure 1, as shown on the attached drawing sheet.

In the Drawings

Please replace Figures 1 and 2 with Figures 1 and 2 on the attached drawing replacement sheet.

Signed and Sealed this
Twenty-fourth Day of October, 2023
